Atty.

UNITED STATES PATENT OFFICE

2,500,722

BOARD GAME INDICATOR

William Walker, Toronto, Ontario, Canada

Application September 7, 1948, Serial No. 48,139

6 Claims. (Cl. 40—124.1)

1

My invention relates to improvements in board games of the indoor variety which are commonly placed upon a table while in use and arranged in front of the seated contestants so that the game can be conveniently played from its playing end. Parlor games of this kind usually have a playing surface upon which game pieces are moved in association with use of chance means, dice, et cetera, according to specified rules and regulations set out by the manufacturer. It is most desirable that such rules and regulations be disposed for convenient reading during the playing of the game in order that a ready reference may be made to them from time to time as occasions require in the progress of the game.

Hence it is the object of my invention to arrange a reference chart or information sheet at an edge portion of a game board to display rules and regulations appertaining to the playing of the games and to support the reference chart or information sheet at a backwardly inclining angle in a manner such that it can be readily collapsed and stored within the game board when not required. According to my invention the reading matter on the reference chart or information sheet is displayed at a most convenient angle for reading while the game is being played. After use of the game board the reference chart or information sheet can be readily collapsed and stored within the board, which preserves it against damage and economizes on storage space. It can be easily pulled out ready for use.

A distinctive feature of the construction is that the so-called information sheet is a plate-like strip of stiff material bearing reading matter attached to a holding device. The holding device is made up of a wing plate, a back plate and a base plate. The wing plate is hinged to the bottom of the information sheet and slidably retained in a pocket open at the top edge of the game board. The back plate is hinged to the top of the information sheet to incline outwardly and downwardly therefrom and is hinged to the base plate. The base plate is slidable in the pocket and has a tab by which it can be pulled to collapse the holding device and draw it into the pocket along with the information sheet.

The invention is illustrated in the accompanying drawing, in which Fig. 1 is a plan view of a game board showing the invention in position for use in playing the game.

Fig. 2 is a sectional elevation on line 2—2 of Fig. 1.

Fig. 3 is a similar view to Fig. 2 but showing the information sheet withdrawn into the pocket of the game board.

Fig. 4 is a perspective view of the game board viewed from its back to show how the tab is operated to collapse the information sheet and its support.

2

For the purpose of illustrating the use of the present invention I have chosen to depict a baseball game comprising the board 1 having on its playing surface a representation of a baseball diamond 2, Fig. 1, on which game pieces (not shown) are moved according to plays indicated by chance means such as dice (not shown). At the playing end 3 of the board there is depicted a scoreboard 4, Fig. 1. It is considered unnecessary to dwell further upon the baseball game per se inasmuch as it does not form a part of the present invention. As a matter of fact the invention is susceptible of use in association with a wide variety of parlor games of the kind herein referred to in which rules and regulations are provided for the moves or plays to be made in the playing of the games. Hence it will be understood that the invention is not confined to the specific game of the illustrative disclosure.

In carrying out the present invention the rules and regulations are printed or otherwise inscribed, as at 5, upon a stiff sheet of material 6, such as pasteboard or millboard. The rules and regulations are captioned "Reference chart" as will be noted from an inspection of Fig. 1 of the drawing. The sheet 6 with the reading matter thereon may be conveniently referred to as an "information sheet," which for facility of reading is disposed at the head end of the board 1 opposite the playing end 3. It is supported by a holding device at a backward inclination to upstand from the board so that it can be viewed by the contestants while they are playing the game.

The collapsible holding device comprises a wing plate 7, a back plate 8 and a base plate 9, all of which are made of stiff material similar to the so-called reference chart 6. The wing plate 7 is hingedly connected at 10 to the bottom of the reference chart and slidably contained in a pocket 11 formed in the board 1. The back plate 8 upstands at a slight backward angle to the rear of said reference chart and is hingedly connected thereto at its top, as at 12. The bottom of the back plate is hinged at 13 to said base plate 9, which base plate projects rearwardly of the board 1 and is slidably contained in the pocket subjacent the wing plate 7.

Suitable means are employed to limit sliding movement of the wing plate in a direction outwardly of the pocket. Said means is shown by way of example but not of limitation as comprising the stop strips 14 and 15, which are arranged transversely. The stop strip 14 is secured to the wing plate to upstand therefrom. The stop strip 15 is secured to the board 1 within the pocket so as to be engaged by the stop strip 14 in the unfolded position of the device, as clearly illustrated in Fig. 2.

A grip piece in the form of a tab 16 is secured to the bottom face of the base plate to project

through a slot 17 provided in the bottom of the board. The tab is grasped by hand to slide the base plate as will be seen by reference to Fig. 4. The slot 17 runs parallel to the direction of movement of the base plate 9 and is of a length to accommodate the required range of travel thereof for the collapsing of the information sheet.

The pocket 11 extends the full width of the board 1 and is formed therein in approved manner as by the upper wall 18 and the lower wall 19 which are marginally joined at opposite sides and also at the playing end 3, thus leaving the head end 20 open in the form of a mouth for inward and outward sliding movement of the wing plate and the base plate.

While the game is in use the information sheet is retained in the convenient reading position shown in Fig. 1, 2 and 4. When the game is to be put away after use the information sheet is collapsed within the pocket by pulling on the tab 16. The tab when drawn toward the playing end of the board causes the base plate to slide completely into the pocket which, in this movement, first swings the lower end of the back plate toward the information sheet and then pulls it into the pocket along with the information sheet. The wing plate slides inwardly of the pocket to accommodate this movement. The folding action is entirely automatic. The information sheet is thus stored in the pocket in a compact manner, as shown in Fig. 3. The tab is pulled in reverse direction to eject the information sheet which automatically unfolds the holding device to supporting position.

While a selected embodiment of the invention has been disclosed as an example of one practical form of the invention, it will be understood that such changes and variations may be resorted to as come within the scope of the appended claims.

What I claim is:

1. The combination in a board game, of a board having a shallow pocket provided with a mouth at an edge portion of the board, an information sheet inclined upwardly and outwardly of said edge portion, a wing plate slideable in said pocket and hinged to the bottom of said information sheet, a subtending base plate also slideable in said pocket, said base plate projecting from said pocket and being provided with handle means, and a back plate hinged to the projecting portion of said base plate and upstanding therefrom, the top of said back plate being hinged to said information sheet so as to collapse the same and draw it into said pocket when said base plate is caused to slide inwardly of said pocket.

2. The combination in a board game, of a board having a shallow pocket provided with a mouth at an edge portion of the board, an information sheet inclined upwardly and outwardly of said edge portion, a wing plate slideable in said pocket and hinged to the bottom of said information sheet, a base plate disposed subjacent said wing plate to slide in said pocket, said base plate protruding from said pocket to the rear of said information sheet, grip means for sliding said base plate, and a back plate upstanding from said base

plate and hinged at the bottom to the rear portion thereof, said back plate also being hinged at its top to the upper portion of the information sheet so as to first collapse the information sheet and then draw it into said pocket when said base plate is withdrawn into said pocket.

3. A structure as set forth in claim 2, in which means is provided to limit outward movement of the wing plate.

10 4. A structure as set forth in claim 2, in which the board includes upper and lower walls which are spaced to form the pocket, and in which the grip means comprises a flexible tab attached to the base plate and projected through a slot provided in said lower wall so that it is accessible from the bottom of said board.

5 5. The combination in a board game, of a board provided with a slot therethrough, said slot having end portions, an information sheet upstanding from said board, means forming a hinge connection for the lower end of said information sheet so that the sheet can swing backwardly, a holding device for supporting said information sheet at a forward angle, said holding device including an upstanding back plate disposed rearwardly of said information sheet and hinged at its top thereto, a base plate slidably arranged on said board and hingedly connected to the bottom of said back plate, and a handle-forming tab attached to said base plate and passed through said slot in said board to project therefrom so that it can be manually grasped and used to collapse said back plate and information sheet, the range of movement of said base plate being limited by engagement of said tab with an end portion of said slot.

6. The combination in a board game, of a board, an information sheet upstanding therefrom, means forming a hinge connection for the lower end of said information sheet so that the sheet can swing backwardly, and a holding device for supporting said information sheet at a forward angle, said holding device including an upstanding back plate disposed rearwardly of said information sheet and hinged at its top thereto, a base plate slidably arranged on said board and hingedly connected to the bottom of said back plate, and handle means for sliding said base plate to collapse said back plate and information sheet, the said structure being characterized in that said board is provided with a shallow pocket having a mouth disposed endwise thereof, and in that said base plate is arranged to slide in said pocket to pull said back plate and said information sheet into said pocket when drawn inwardly of said mouth.

WILLIAM WALKER.
